Primary Examiner—Wallace R. Burke*Assistant Examiner*—H. Baynham*Attorney, Agent, or Firm*—Francis X. LoJacono**[57]****CLAIM**

The ornamental design for a water hose straightener, as shown and described.

DESCRIPTION

FIG. 1 is a front perspective view of a water hose straightener showing my new design;

FIG. 2 is a rear elevational view thereof;

FIG. 3 is a top plan view thereof; and,

FIG. 4 is a bottom plan view thereof;

The coiled portion of the claimed design along with the shaft member are shown broken away to indicate indeterminate length.

FIG. 1

FIG. 3

FIG. 4
